UNITED STATES PATENT OFFICE.

CARL DUEKER, OF COOPER TOWNSHIP, WEBSTER COUNTY, IOWA.

SNAPPING MECHANISM FOR CORN-HUSKING MACHINES.

Application filed April 24, 1920. Serial No. 376,233.

To all whom it may concern:

Be it known that I, CARL DUEKER, a citizen of the United States of America, and resident of Cooper Township, Webster County, Iowa, have invented a new and useful Snapping Mechanism for Corn-Husking Machines, of which the following is a specification.

The object of this invention is to provide improved means for snapping ears from corn-stalks.

A further object of this invention is to provide improved means for supporting and driving snapping devices in a corn harvester.

15 A further object of this invention is to provide improved means for directing snapped corn laterally from snapping rollers in a corn harvester.

20 A further object of this invention is to provide improved means for supporting snapping rollers in steeply inclined positions whereby the same may straddle, act on and pass freely from standing cornstalks.

25 My invention consists in the construction, arrangement and combination of elements hereinafter set forth, pointed out in my claims and illustrated by the accompanying drawing, in which—

30 Figure 1 is a plan illustrating my improved devices. Figure 2 is a front elevation and Figure 3 a side elevation of the same. Figure 4 is an enlarged detail view illustrating the gear assembly employed to drive the snapping mechanism and other elements. Figure 5 is a cross section on the indicated line 5—5 of Figure 3, on an enlarged scale. Figure 6 is a cross section, on an enlarged scale, on the indicated line 6—6 of Figure 3.

35 40 This invention relates to snapping mechanism and means for driving the same and also is shown and described in part, but not claimed, in my companion application for gathering mechanism for corn harvesting machines pending concurrently herewith.

45 In the construction of the machine and devices as shown the numeral 10 designates an I-beam adapted to be carried on and project laterally from a vehicle such as is shown and described in my companion application for land vehicles filed March 25, 1920, Serial No. 368,705, pending concurrently herewith and finds its counterpart in my other companion application above noted. Angle bars 14, 15, 50 55 16 and 17 are arranged side by side in steeply

inclined planes and are fixed at their upper ends to and extend beneath the I-beam 10. The angle bars 14 and 17 are bent at 18 and extend forwardly from the bend, being broken off in this instance to economize space. 60 The angle bars 15 and 16 are located between and spaced from the angle bars 14 and 17, are slightly spaced apart for the passage of corn-stalks between them, are fixed to and extend beneath the beam 10, and are secured 65 to the beam 10 and, respectively, to the outside angle bars 14 and 17. A shaft 45 is arranged above and substantially parallel with the I-beam 10, is mounted for rotation in suitable bearings 46, 47 carried by the angle 70 bars 14 and 17 and is adapted to be driven by mechanism on or associated with the land vehicle above noted. Tumbling rods 48, 49 are journaled at their upper ends in bearings 50, 51 carried by the bearings 46, 47 and are 75 adapted to be connected to gathering mechanism shown in my other companion application above noted. Bevel-gears 54, 55 on the shaft 45 mesh with bevel-gears 56, 57 on the upper ends of the tumbling rods 48, 49 80 and drive said rods in opposite directions. Snapping rollers 58, 59 are mounted in steep vertical planes in front of the angle bars 15, 16 and overlap them toward the angle bars 14, 17. The snapping rollers 58, 59 are journaled at their lower ends in suitable bearings 85 60 carried by the angle bars 14, 15, 16 and 17 and connect said angle bars in pairs. The snapping rollers 58, 59 are provided with intermeshing spur gears 61, 62 at their upper 90 ends and a bevel-gear 63 is mounted on the roller 58 contiguous to the spur-gear 61 and meshes with and is driven by a bevel-gear 64 on the shaft 45. A yoke 65 is mounted on the angle-bar 16 and a stub shaft is journaled 95 in the central portion of said yoke and carries a wrist-wheel 66 on one end and a bevel-gear 67 on the opposite end, which bevel-gear meshes with and is driven by a bevel-gear 68 on the shaft 45. Angle bars 69, 70 100 and 71 are mounted on and extend forwardly and upwardly from the angle bar 17 and cross at one side of the snapping roller 59. Arms 72 of looped form, one for each angle bar 69, 70 and 71, are pivoted at one end 105 each in said angle bars and extend laterally across the center, and in front of the snapping roller 59. An agitator or baffle 73 is pivoted to and carried by inner ends of the arms 72 and occupies a position parallel with, 110

slightly spaced from and in front of the snapping roller 59, said agitator being located between the line of demarkation between the snapping rollers and the center of 5 said roller 59. A pitman 74 is pivoted at one end to the upper end of the agitator or baffle 73 and is pivoted at its other end, in decentered relation, to the wrist-wheel 66. Thus provision is made for transforming rotary motion of the wrist wheel 66 into reciprocatory motion of the agitator or baffle 73. A bearing block 75 (Figure 5) is mounted on the beam 10 and a bearing is formed in one end thereof together with a cap 76 10 secured thereto and is adapted to receive and journal the upper end portion of the snapping roller 58 or its shaft. A bearing 77 is mounted in a slide seat in the opposite end of the block 75 and is confined by a cap 78 15 mounted on said block opposite to the cap 76, a compression spring 79 being interposed between the cap 78 and the bearing 77. The upper end portion of the snapping roller 59 or its shaft is journaled in the bearing 77. 20 25 A similar cushioned bearing is provided in one of the bearings 60 to accommodate the lower end of the roller 58. Thus provision is made for yieldingly mounting one of the snapping rollers to compensate for an over-load occasioned by passing between them of cornstalks or other objects. In Figure 6 the snapping rollers 58, 59 are shown in detail in cross section. The roller 58 is shown with arcuate spiral grooves 80 in its periphery, 30 35 each of said grooves forming edges 81. The roller 59 is shown with opposite spiral grooves 82, the portions 83 of the periphery between said grooves being on right lines having outward curves between them and forming edges at the sides of the grooves 82. Corn-stalks are accommodated in the grooves 80. The snapping rollers 58, 59 have been described as inter-connected through the spur-gears 61, 62, whereby they are driven in 40 45 unison, and the intermeshing of said spur-gears is deep enough to compensate for any springing apart that may be occasioned by corn-stalks passing between the rollers, it being understood that only the smaller upper portions of the corn-stalks pass between said rollers in proximity to the spur-gears. However, the rollers do spring apart to permit the corn-stalks to pass between them under the effect of the oppositely rotating rollers and the edges 81 of one roller coact with the grooves 82 of the other roller to pinch and sever the stems of the ears from the stalks, thus snapping the ears, generally with their 50 55 husks, from the stalks.

In practical use the shaft 45 serves as a 60 driver and, acting through the shafts and rollers as above described and the tumbling rods rotates them oppositely in such manner as to involutely drive the snapping rollers 58, 59 and tumbling rods. It is the function of 65 the snapping rollers to snap the ears from the stalks and the gear ratio employed is such that all of the stalks and forage thereon is left in the best possible condition after it has passed between the rollers. It is the function of 70 the agitator or baffle 73 to prevent ears of corn, alone or contained in their husks, being carried over the snapping roller 59. Suitable receiving means may be employed at the foot of the snapping rollers 75 for the ear corn snapped from the stalks thereby and suitable elevating, conveying, husking and other driving mechanism may be supplied therefor, the same forming no 80 part of my present invention and, consequently, not being shown.

I claim as my invention—

1. In a snapping mechanism for corn-husking machines, a pair of snapping rollers, one of said rollers being formed with arcuate spiral grooves in its periphery alternating with spiral ribs having spiral edges thereon, the other roller being formed with spiral grooves of less depth and width than the 85 grooves of the first mentioned roller and adapted to receive the ribs thereof, said ribs having rounded apices in cross-section with plane surface connections with adjacent grooves, said apices not contacting when operating with the bottoms of the grooves. 90 95

2. In a snapping mechanism for corn-husking machines having a frame and rollers journaled side by side in said frames, an agitating device and means for supporting and operating the same, adapted to be employed with said frame and rollers, said device and means comprising angle bars fixed to said frame and extending outwardly therefrom across the plane common to said rollers, looped arms pivoted at one end each to said angle bars and extending laterally therefrom partially across the nearer roller, the axes of articulation of the arms being parallel with the angle bars, said agitator device being arranged wholly in front of said nearer roller and pivotally mounted on the otherwise free ends of said arms, and a driven pitman connected with one end and extending longitudinally of said agitator. 100 105 110

Signed at Fort Dodge, in the county of Webster and State of Iowa, this 6 day of April, 1920.

CARL DUEKER.
